UNITED STATES PATENT OFFICE.

LOUIS A. KLING, OF EAST CLEVELAND, OHIO, ASSIGNOR TO THE J. G. BRILL COMPANY,
OF PHILADELPHIA, PENNSYLVANIA, A CORPORATION OF PENNSYLVANIA.

DOOR-OPERATING MECHANISM.

1,178,232.

Specification of Letters Patent.

Patented Apr. 4, 1916.

Application filed May 19, 1913. Serial No. 768,595.

To all whom it may concern:

Be it known that I, LOUIS A. KLING, a citizen of the United States, residing in East Cleveland, county of Cuyahoga, State of Ohio, have invented certain Improvements in Door-Operating Mechanism, of which the following is a specification.

One object of my invention is to provide mechanism for opening and closing doors, particularly the doors of passenger cars, by power or manually driven mechanism controlled, in the present instance, by the foot.

A further object of the invention is to provide means for operating a plurality of doors, either in unison or singly, as desired.

A still further object of the invention is to locate operating means at the floor of the platform, so that it can be controlled by the foot of the conductor or other operator.

My invention can also be used in connection with folding step mechanism, so that the steps can be raised and lowered simultaneously with the closing or opening of the doors.

In the accompanying drawings:—Figure 1, is a sectional plan view of the vestibule portion of a central entrance passenger car, showing the doors open; Fig. 2, is a vertical sectional view on the line *a—a*, Fig. 1, showing the doors closed; Fig. 3, is an enlarged plan view of the operating mechanism located at the floor of the car; Fig. 4, is a longitudinal sectional view on the line *b—b*, Fig. 3; Fig. 5, is a sectional view on the line *c—c*, Fig. 3; Fig. 6, is a perspective view of one of the treadle plungers; Fig. 7, is a detached perspective view showing the ratchet connection; Fig. 8, is a diagrammatic plan view illustrating independent solenoid motors for each door, with a common switch plate; Fig. 9, is a view illustrating the mechanism by which the folding step is actuated in unison with the doors; Fig. 10, is a plan view showing the sliding door at each side and a central hinged door; Fig. 11, is a plan view in which all the doors are hinged, and Figs. 12 and 13, are views showing the hand operating mechanism.

Referring to the drawings, 1 is the body of a passenger car, in the present instance of the type known as the "central entrance," *i.e.*, a car having an entrance at the center instead of at either end. At the present time, these cars are designed without a step; the floor 3 of the vestibule being slightly

elevated above the level of the street, so that it is not necessary to provide a step, although a step may be used without departing from the essential features of the invention. The entrance to the car may be at the center, as illustrated in the drawings, or at either end, the novel features of the invention relating particularly to the mechanism for operating the doors, not only those of passenger cars, but, in fact, those of any building or other structure where the doors are actuated from a given point either by power driven mechanism or by hand.

In the present instance, 4 and 5 are two posts, which separate the central ingress passageway from the two exit passageways.

6 indicates a pair of folding doors secured to a vertical pivot rod 7 at the post 5.

8 indicates a pair of folding doors mounted on a pivot rod 9 at the side of one of the exit passageways, and 10 is a sliding door arranged to close the other exit passageway and to slide within the casing of the car.

The above arrangement is used to illustrate the invention, but it will be understood that all of the doors may be pivotally mounted, as in Fig. 11, or the center door may be pivotally mounted and the side doors may slide, as in Fig. 10, and the mechanism may be used with one, two or more doors.

11 is a central rail inclosing the fare box 12 at the back of which is the conductor's station *a*.

13, 13 are guard rails extending from the center of the car at each side of the vestibule to the posts 4 and 5, respectively, which separate the entrance and exit passageways.

14 is a plate set in the floor of the vestibule at the conductor's station, and 15, 16 and 17 are treadle plungers which project above the floor and which can be depressed by one foot of the operator. The three plungers are so grouped that they can be depressed by one movement of the foot; or one or all of the plungers can be depressed as the conductor desires and conditions require.

In the present instance 18 is an electric motor, mounted in suitable bearings above the floor of the car vestibule. On the armature shaft 19 of this motor is a worm 20 which meshes with a worm wheel 21 on a vertical shaft 22 having its bearings in the plate 14 and the casing 23 located under the plate, as illustrated in Fig. 4, which in-

cludes the clutch mechanism. The plate and the casing are secured to the floor by bolts 24. The worm wheel 21 is loose on the shaft 22, and I preferably connect the worm wheel 21 with the main shaft 22 by a slip friction clutch, so that, when an obstruction prevents the movement of the doors, the clutch will automatically release and the door will be prevented from moving. This clutch consists of a disk 71 having a series of balls 72 adapted to recesses in the underside of the worm wheel 21, which is loose on the shaft 22. The disk 71 is keyed on the shaft so that while it can slide thereon it must turn therewith. Back of this disk 71 is a spring 73 which tends to hold the balls in the recesses, but should the obstruction prevent the movement of the driven element then the spring 73 will be compressed and the worm wheel 21 will turn freely on the shaft 22. Secured to the shaft 22 is a pinion 27 which meshes with the gear wheels 28, 29 and 30, Fig. 3, mounted loosely on spindles 31, 32 and 33, respectively. These spindles are connected to the lever mechanism controlling the several doors. The gear wheel 28 has teeth 34 which mesh with teeth 35 on a clutch sleeve 36 arranged to slide on and turn with the spindle 31. A lever 37, pivoted at 38 to the casing, is forked at one end, and on the forks are pins which enter an annular groove in the clutch sleeve 36. The other end of the lever 37 extends under the treadle plunger 15 and is recessed for the reception of the plunger, so that, when the plunger 15 is depressed by the foot of the operator, the teeth of the clutch sleeve 36 are forced into mesh with the teeth 34 on the gear wheel 28, causing the spindle 31 to rotate with the shaft 22. On this spindle 31 is an arm 39 connected by a rod 40 to an arm 41 on the vertical pivot rod 7 of the central door 6. If the door 6 is in the closed position, as in Fig. 2, by placing a foot on the treadle plunger 15, it throws the parts into gear and the arm 39 is turned, causing the said door 6 to swing to the open position, as illustrated in Fig. 1. If the foot of the operator is not withdrawn from the treadle plunger, the door will swing to the open and then to the closed position, as the arms 39 and 41 are so arranged that while the arm 39 rotates in one direction, the rotation of the arm 40 will merely cause reciprocation.

In order to lock the door in either the closed or the open position, I form lugs 42 on the casing 23 on each side of the bearing for the spindle 31, as illustrated in Fig. 7. In the underside of the clutch sleeve 36, I form notches 43 and bevel the face of the sleeve on one side of each notch, as at 44, Fig. 7, so that when the foot of the operator is taken off the treadle plunger, when the door is open, for instance, the sleeve will

be carried until the notches are directly above the lugs 42, when it will drop into position and clear the teeth 34 of the gear wheel 28. Springs 45 are adapted to sockets in the sleeve 36 and rest against a flange 46 on the spindle 31, Fig. 5, so that as soon as the clutch sleeve is released, the spring will force it away from the wheel 28, so that the plunger 15 is projected into its normal position. When the doors are full open or closed the arm 39 and rod 40 are on a straight line, making, in fact, a double lock for the door. Instead of the three springs 45 shown, a single spring may be used which will encircle the spindle, if found desirable.

The wheels 29 and 30 have clutch teeth similar to the wheel 28. There is a clutch sleeve 47 under the wheel 29 and a clutch sleeve 48 under the wheel 30. These sleeves are adapted to turn with and to slide on the spindles 32 and 33, respectively. The clutch sleeve 47 is controlled by a lever 49 and the clutch sleeve 48 is controlled by a lever 50 directly under the plungers 16 and 17, respectively. The details of these devices are similar to the mechanism for operating the central door.

The spindle 32 has an arm 51 connected by a rod 52 to an arm 53 on the pivot rod 9 of the door 8, and on pressing the plunger 16 the mechanism will be connected so as to close or open the door. The spindle 33, in the present instance, has an arm 54 which is connected by a rod 55 to an arm 56 on a rock shaft 57 mounted in bearings under the floor of the car. At the opposite end of this shaft 57 is a long arm 58 which extends into the door channel at the side of the car and has a pin which enters a slot in a bracket 59 secured to the rear edge of the door 10. This door 10 has rollers 60 at the upper edge which travel on rails 61 so that when the plunger 17 is depressed, the shaft 57 will be rocked and the door will be moved either to the open or the closed position.

The doors 6 and 8, in the present instance, are made in two parts connected by hinges. The outer part of each door is hung from a rail 62 by a guide wheel 63 in the ordinary manner, so that, when the doors are opened, the guide will travel in the rail and will cause the two parts of the door to fold together, as in Fig. 1.

The motor and the gearing 20 and 21 are inclosed by any suitable casing 64, Fig. 4, when mounted above the floor of the vestibule.

In Fig. 8, I have shown the doors actuated by solenoid magnets 65. The core of each pair of magnets is connected to a door and the mechanism is controlled by two switch boards 66, 67 located at any convenient point within reach of the conductor or other operator.

In Fig. 9, I have shown the mechanism in

8c

85

95

100

105

110

115

120

125

connection with a folding step. On the rod 40 which extends to the door is a bracket 68, and pivoted under the floor of the platform at the edge thereof is a step 69 and a rod 70 connects the step with the bracket 68 on the rod 40.

In the event of the motor, or other power driving mechanism, being out of order, the shaft 22 can be turned by hand as it is extended, in the present instance as illustrated in Fig. 2, to a point near the upper portion of the guard rail, and is provided with a head to which a handle can be applied, as in Fig. 12.

15 The clutch disk 71 is connected to a rod 74 extending through the shaft, by a pin 75, and the rod is provided with a button 76 at the upper end, so that the operator can immediately press on the button and throw 20 the disk and its balls out of contact with the power driving worm wheel 21, if he sees any one being caught by the door, and, in order to throw the power driving mechanism out of gear when the mechanism is to be operated manually, I provide a capped hand lever 77, Fig. 12, which is arranged to engage a notched head 78 at the upper end of the shaft 22 and extends over the button 76 and, when the lever is pressed down, a catch 25 79 engages the head 78 of the shaft and holds the rod 74 in the depressed position and the clutch out of gear.

In some instances the mechanism may be manually operated during certain hours of the day and power operated during other hours, say the rush hours.

It will be seen by the above construction, that I provide an effective means for opening and closing the doors of a passenger car. 40 The mechanism is not complicated in construction and is easily actuated by the operator placing one foot on one or more of the treadles; the hands of the operator being free for the performance of his other duties, such as collecting fares, etc.

I preferably use the treadle plunger shown in Fig. 6, having two lugs 80 and 81 offset as shown, so that the plunger when passed through a slot in the plate and turned is 50 prevented from accidentally jumping out and cannot be maliciously removed without some trouble.

In some types of cars, this mechanism may be controlled by the motorman, instead 55 of by the conductor, in which case his hands would be free to operate the controller and the brake.

While particularly adapted for use in connection with passenger cars, the device, as 60 stated above, may be used for opening and closing doors in buildings, or may be used in connection with gates which are opened and closed by an attendant.

While I have shown an electric motor, any 65 other type of motor may be substituted for

it. Where the mechanism is located in a building, any suitable power shaft may be geared to it, or the main shaft may be turned by hand, if desired, or where power is not convenient.

When it is desired to open any one of the doors, the plungers can be depressed and the door operating mechanism clutched to the driven shaft, and one door after another can be opened. It is not necessary to wait until 70 the first door is full open as the mechanism is thrown in action as soon as a treadle is pressed and, after the door commences to move, the operator can take his foot off the treadle and the door will automatically stop 75 when full opened or closed.

While I have shown the treadle plungers at the floor, so as to be operated by the foot, it will be understood that they can be raised so as to be operated by one hand of the 80 operator, if found desirable.

I claim:—

1. The combination of a door; a vertical driven shaft; a vertical spindle; a gear wheel on the driven shaft; a gear wheel 90 loose on the spindle, the latter gear wheel having a clutch face; a clutch sleeve arranged to turn with but slide on the spindle; a lever for throwing the clutch sleeve into and out of engagement with the clutch 95 face of the gear wheel; an arm on the spindle; and means connecting the arm to the door, so that the door is opened and closed on the movement of the clutch sleeve.

2. The combination of a floor; a door for 100 controlling the passage over the floor; a casing mounted in the floor; a driven shaft adapted to bearings in the casing; a gear wheel on the shaft; a spindle mounted in the casing; said spindle having a gear wheel 105 loose thereon and meshing with the first mentioned gear wheel; the last mentioned gear wheel having a clutch face; a clutch sleeve movable on the spindle; means connecting the sleeve so that the spindle turns 110 with it; an arm on the spindle connected to the door; a lever engaging the clutch sleeve and adapted to the casing; and a plunger projecting through the casing and arranged to be actuated by one foot of the operator 115 so as to throw the clutch into mesh with the clutch face on the gear, causing the door to be opened or closed.

3. The combination of a floor; a door controlling the passage over the floor; a casing 120 mounted in the floor; a vertical shaft mounted in bearings in the casing; a motor mounted on the floor and having a shaft geared to the vertical shaft; a vertical spindle mounted in bearings in the casing; a gear wheel secured to the vertical shaft; a gear wheel loose on the spindle and meshing with the first mentioned gear wheel, said last mentioned gear wheel having a clutch face; a clutch sleeve secured to turn with said 125 130

spindle having a clutch face arranged to engage the clutch face of the gear wheel; means connecting the spindle with a door; means for actuating the clutch sleeve; and 5 a clutch located between the motor shaft gearing and the vertical shaft.

4. The combination of a floor; a door for controlling the passage over the floor; a casing located in the floor some distance 10 from the door; a vertical driven shaft mounted in the casing; a gear wheel on the shaft; a spindle also mounted in the casing; a gear wheel loose on the spindle and meshing with the gear wheel on the first mentioned shaft; said last mentioned gear wheel having a clutch face; a clutch sleeve arranged to slide on but turn with the spindle; a lever adapted to bearings in the casing for actuating the clutch sleeve; a treadle 15 plunger for operating the lever; a rock shaft connected to the door; an arm on the rock shaft; an arm on the spindle; and a rod connecting the arm on the spindle with the arm on the rock shaft; the parts being 20 so arranged that as the spindle rotates the rock shaft will turn part of a revolution first in one direction and then in the opposite direction.

5. The combination of door operating 30 mechanism; a driven shaft; separate spindles; doors to which the spindles are connected; clutch mechanism for each spindle through which the spindles are driven from

the shaft; a lever for each spindle, the actuating ends of the levers being grouped close 35 together, so that one, two or three spindles can be depressed at one operation.

6. The combination of a door; a driven shaft; a spindle; clutch mechanism between the spindle and the driven shaft; mechanism 40 connecting the spindle with the door, so that, when the clutch is thrown into mesh, the door will be opened or closed; and means, at the clutch, for locking the door either in its closed or in its open position. 45

7. The combination of a door; a driven shaft; a gear wheel on said shaft; a spindle connected to the door; a gear wheel loose on the spindle and meshing with the first mentioned gear wheel; a sliding clutch sleeve 50 arranged to turn with the spindle and to engage the last mentioned gear wheel; a lever for operating the clutch sleeve; a casing in which the spindle is mounted, said casing having a lug, the clutch sleeve being 55 notched to receive the lug when the clutch sleeve is withheld from engagement with its gear wheel.

In testimony whereof, I have signed my name to this specification, in the presence of 60 two subscribing witnesses.

LOUIS A. KLING.
